UNITED STATES PATENT OFFICE.

FRANK KALATA, OF SPRINGFIELD, ILLINOIS.

MINE-DRILL.

1,305,219.

Specification of Letters Patent. Patented May 27, 1919.

Application filed January 24, 1919. Serial No. 272,849.

To all whom it may concern:

Be it known that I, FRANK KALATA, a citizen of Poland, residing at Springfield, in the county of Sangamon and State of Illinois, have invented certain new and useful Improvements in Mine-Drills, of which the following is a specification.

The primary object of the invention is the provision of a drilling device serviceable in a mine and comprising a bit and a readily separable holder therefor, the structure possessing great strength and one bit being easily and quickly replaced by another when the bit becomes dull or broken.

15 A further object of the invention is the provision of a form of bit and holder in which the bit is readily detached from the holder when desired and is automatically held therein upon insertion of the holder.

20 With these general objects in view, the invention consists of the combination and arrangement of parts hereinafter fully described in connection with the accompanying drawing and in which like reference 25 characters designate corresponding parts throughout the several views.

In the drawings,

Figure 1 is an elevational view of the invention with parts broken away.

30 Fig. 2 is a longitudinal sectional view taken upon line II—II of Fig. 1.

Figs. 3 and 4 are transverse sectional views taken upon lines III—III and IV—IV respectively of Fig. 1, and

35 Fig. 5 is a perspective view of the attaching end or tang portion of the bit.

Referring more in detail to the drawing, my invention broadly includes a socket 11 secured upon the end of the boring or drill 40 shaft 12 by means of holdfast devices 13, a bit or drill 14 being adaptable for detachable connection with the socket 11.

The bit 14 has a sharpened drill portion 15 with a tang 16, oval in cross section with 45 cut-away side portions or notches 17 forming a head 18 upon the free end of the tang 16. The socket member 11 has an oval bore 19 axially thereof for the reception of the tang 16, the head 18 of the tang being received within the inner end portion or socket 50 20 of the member 11 when the device is assembled. Substantially T-shaped openings 21 in the opposite sides of the socket member 11 communicate with the bore 19.

55 A jaw 22 is pivoted by means of a pin 23 within the openings 21 in such a manner

that the outer faces of the jaws 22 normally lie flush with the adjacent outer sides of the socket member 11.

The enlarged end portions 24 of the jaws 22 are thinner than the narrower end portions 25 of the jaws which are in the form of blocks adapted for engaging within the notches 17 of the tang 16 for retaining the bit 14 connected to the socket member 11. 60 Leaf springs 26 are secured by screws 27 to the inner faces of the block portions 25 of the jaws 22 and extend to points inwardly of the thinner jaw portions 24 and resiliently bear upon opposite ledges 27' 65 surrounding the bore 19 adjacent the outer ends of the openings 21. It will be noted that the openings 21 are in the form of cut-away portions and provide the ledges 27' heretofore referred to so that the communication with the sides of the bore 19 extends between the inner ends 30 of the ledges 27' 70 and the inner ends 31 of the said openings 21. 75

The springs 26 normally hold the block 80 portions 24 of the jaws pressed inwardly so that the forcible entrance of the tang 16 into the bore 19 engages the block portions 24 in the notches 17 when the head 18 of the tang 16 seats within the inner socket 85 portion 20 of said bore 19. At such times, the end face 28 of the head 18 flatly engages the bottom 29 of the socket 20 which forms the inner end of the bore 19 so that the bit is held in the socket member in such a manner 90 that the downward movement of the drill shaft 12 acts directly upon the tang head 28 of the bit 14 during the drilling or boring operation.

When it is desired to remove the bit 14 95 from the socket member 11, the portions 24 of the jaws 22 are depressed and the jaws rocked upon their pivot 23 which disengages the block portion 25 thereof from their engagement with the sockets 17 of the 100 bit tang 16, releasing the head 18 and permitting the removal of the tang 16 from the bore 19. A structure of great strength is provided, one that is of simple construction, the bit being instantly secured in and removed from the socket member 11 when desired. 105

What I claim as new is:—

1. A device of the class described comprising a socket member having an axial bore 110 oval in cross section and with substantially T-shaped opposite openings through the

- sides of the socket member communicating with said bore and forming ledges at opposite sides adjacent the open end of the bore and a socket at the inner end of the bore, 5 jaws pivoted within said openings having block portions normally projecting into said bore and relatively thin and wide finger engaging portions outwardly of said ledges and positioning springs secured to the inner 10 sides of the block portions of the jaws and bearing upon said ledges, whereby the outer faces of the jaws are normally maintained flush with the opposite outer faces of the socket member.
- 15 2. A device of the class described comprising a socket member having an axial bore oval in cross section and with substantially T-shaped opposite openings through the sides of the socket member communicating 20 with said bore and forming ledges at opposite sides adjacent the open end of the bore and a socket at the inner end of the bore, jaws pivoted within said openings having block portions normally projecting into said 25 bore and relatively thin and wide finger engaging portions outwardly of said ledges, positioning springs secured to the inner sides of the block portions of the jaws and bearing upon said ledges, whereby the outer faces of 30 the jaws are normally maintained flush with the opposite outer faces of the socket member, a bit having a tang oval in cross section adapted for removable reception within said bore, the said tang having opposite notches 35 forming a head at the free end of the tang, the said head being adapted for seating within the socket portion of the bore with the block portions of said jaws engaging within said notches when the device is assembled.
- 40 3. A device of the class described comprising a socket member for a drill having an axial bore open at the end of the socket and terminating in an end face located therein, the said socket member having substantially T-shaped cut-away portions in its opposite 45 sides providing openings communicating with said bore spaced from the inner end of the latter and forming opposite ledges spaced from the open end of the bore, substantially 50 T-shaped jaws pivoted in said cut-away portions with relatively thin and wide ends overlying said ledges and relatively narrow and thick block portions within said openings normally projecting within the bore at a distance from the inner end of the bore, and 55 normal positioning springs for the jaws attached to the block portions thereof and resiliently engaging the outer faces of said ledges.
4. A device of the class described comprising a socket member for a drill having an axial bore open at the end of the socket and terminating in an end face located therein, the said socket member having substantially 60 T-shaped cut-away portions in its opposite sides providing openings communicating with said bore spaced from the inner end of the latter and forming opposite ledges spaced from the open end of the bore, substantially 65 T-shaped jaws pivoted in said cut-away portions with relatively thin and wide ends overlying said ledges and relatively narrow and thick block portions within said openings normally projecting within the bore at a distance from the inner end of the bore, and 70 normal positioning springs for the jaws attached to the block portions thereof and resiliently engaging the outer faces of said ledges, a bit member having a tang adapted for removable reception within said 75 bore provided with side notches adapted for the reception of the block portions of the jaws when the free end portion of the tang is seated in the inner end portion of the bore in engagement therewith when the device is 80 assembled for use.
- In testimony whereof I affix my signature.
FRANK KALATA.
